US0D1025951S

(12) **United States Design Patent** (10) **Patent No.:** **US D1,025,951 S**
(45) **Date of Patent:** **** May 7, 2024**

(54) **HEADPHONE CONTROLLER**

(71) Applicant: **CYD Electronics (Shenzhen) Co., Ltd**,
Shenzhen (CN)

(72) Inventor: **Huaqiong Mai**, Shenzhen (CN)

(73) Assignee: **CYD Electronics (Shenzhen) Co., Ltd**,
Shenzhen (CN)

(**) Term: **15 Years**

(21) Appl. No.: **29/881,377**

(22) Filed: **Dec. 30, 2022**

(51) LOC (14) Cl. **14-01**

(52) U.S. Cl.

USPC **D14/205**

(57) **CLAIM**

The ornamental design for a headphone controller, as shown and described.

DESCRIPTION

FIG. 1 is a front, right and bottom perspective view of a headphone controller, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the headphone controller that form no part of the claimed design.

1 Claim, 8 Drawing Sheets
